UNITED STATES PATENT OFFICE.

BYRON B. GOLDSMITH, OF NEW YORK, N. Y.

ERASER-HOLDER FOR LEAD-PENCILS.

No. 854,487.

Specification of Letters Patent.

Patented May 21, 1907.

Application filed December 29, 1906. Serial No. 349,930.

To all whom it may concern.

Be it known that I, BYRON B. GOLDSMITH, a citizen of the United States, residing at New York, in the county of New York, in the 5 State of New York, have invented a new and useful Eraser-Holder for Lead-Pencils, of which the following is a specification.

My invention has reference to improvements in eraser holders for lead pencils, the 10 main feature of the invention being to provide a short holder for the reception of an eraser block of greater length than the length of the holder, so as to project at both ends from the same, and to provide the butt end 15 of the lead pencil with a housing for the eraser holder, which can thus be removed from the housing and reinserted either in a reversed position so as to expose a new eraser surface for use, or in the original position 20 after the eraser block has been fed outwardly so that it can be used up through the greater part of its length.

In the accompanying drawing, which forms a part of this specification the invention is illustrated as follows:

Figure 1 is an elevation of a lead pencil provided with one form of removable eraser holder, and Fig. 2 is a longitudinal section thereof, partly in elevation. Figs. 3, 4 and 5 30 illustrate another form of the invention in elevation, longitudinal section and perspective, respectively, and Figs. 6, 7 and 8 are like views of still another form which the invention may assume.

Like numerals of reference indicate like parts all throughout the drawing.

In these drawings, in Figs. 1, 2, 3 and 4, the lead pencil 1 is shown as of an ordinary cylindrical type, and to the butt end of the 40 pencil is secured in irremovable fashion a ferrule 2, in the usual manner as by indentations 3, made in the ferrule after it has been slipped over the butt end of the pencil, and by which a part of the metal of the ferrule is driven into the wood of the pencil. 45 This is the ordinary mode of securing a ferrule to a lead pencil, but any other means may be employed. In Figs. 1 and 2 there is shown an internal screw thread 4 at or near 50 the rear end of the ferrule, for the reception in a detachable and reversible fashion of the eraser holding sleeve or tube 5. This eraser holding sleeve or tube, which is rather short, has formed at each end a screw thread, spun 55 into the sleeve, so as to serve both as a female and male screw, and between these

two screw threads is a milled bead 6, which serves two purposes. It serves as a finger hold by which the sleeve or tube is grasped for screwing either end of it into the rear end 60 of the ferrule, and it also serves as a stop, limiting the extent to which the sleeve or tube can be screwed into the ferrule. This sleeve or tube 5 is the real eraser block holder, and in the form shown in Figs. 1 and 2 the eraser 65 block 7, may be either of uniform structure all throughout its length or may be formed through one half of its length as a pencil eraser and through the other half of its length as an ink eraser. The eraser block 70 being considerably longer than its holder it projects, when centrally seated, beyond each end of the same. If the block is made uniform throughout it can be fed outwardly, 75 after its exposed portion has been used up, by unscrewing the sleeve or tube and holding it in one hand and turning the rubber in the proper direction by the other hand, since the rubber block is screwed into the sleeve or holder. In this manner double the length 80 of the eraser block can be utilized than with ordinary holders in which the eraser block is not adjustable. If, however, the eraser block is formed throughout one half of its 85 length as a pencil eraser and throughout the other half of its length as an ink eraser, either of the two ends can be used by unscrewing the holder and inserting it into the ferrule with the other end. The end of the eraser block which is not in use at a given 90 time is protected from soiling by being housed in the ferrule.

In the form shown in Figs. 3, 4 and 5 the ferrule is not screw-threaded, nor is the eraser holding sleeve. The latter is split, as indicated at 8, and has in addition thereto a number of longitudinal slots 9, whereby the sleeve is rendered elastically expansible and the eraser block is held therein frictionally. The sleeve itself is inserted into the ferrule 100 by slightly compressing it about the eraser block and forcing it into the ferrule longitudinally, where it is then held frictionally and safely, the bead 6 serving, as in the case of Figs. 1 and 2, both as a finger hold and as a 105 stop. With this construction the eraser block would be made all throughout uniformly, either as a pencil or as an ink eraser, and when the outwardly projecting end has been used up another portion can be projected 110 for use by removing the holder from the ferrule and pushing the block outwardly from

the rear, which can be easily done, since the sleeve or holder is expansible.

In Figs. 6, 7 and 8 the eraser holding sleeve or tube is constructed the same as shown in Figs. 2, 4 and 5, but it is here specially adapted for use on a lead pencil that is considerably thicker at the butt end than at the writing end. Such pencils have been in use for a long time, and in order to adapt it for the reception of the expansible eraser block holder 5, a special construction must be employed. As shown in Fig. 7 there is formed in the butt end of the pencil an axial cylindrical cavity 10, of sufficient length to receive the sleeve 5 with its rearwardly projecting eraser block. Over the butt end of the pencil is mounted a ferrule 2', which is dome shaped where it projects beyond the butt end of the pencil, and has there a circular opening, which permits the entrance of the sleeve 5. This sleeve 5 is provided with a shallow circumferential groove or depression 5' next to the bead 6, and when the sleeve is inserted through the opening in the dome shaped ferrule 2 and is pushed into the cavity 10, the edge 11 of the opening of the dome shaped ferrule snaps into this groove 5' and thus elastically clamps the eraser holder in position. The diameter of the cavity 10 is, as indicated in Fig. 7, slightly greater than that of the opening in the dome shaped ferrule 2', so that the sleeve 5 is not frictionally held, to any particular extent, in that cavity, but is safely held by the engagement of the edge 11 with the groove 5'. While the groove 5' contributes to the secure holding of the eraser holding sleeve 5, it is not absolutely essential, since even in the absence of the groove the edge of the opening of the dome shaped ferrule would have sufficient hold upon the sleeve, even in the absence of the groove.

Having now fully described my invention

what I desire to secure by Letters Patent is:

1. The combination of a lead pencil provided with a ferrule irremovably secured to its butt end, an open ended eraser holder detachably fitted to the ferrule, and an eraser block projecting from each end of the holder, substantially as described. 4

2. A lead pencil provided with a ferrule irremovably secured to its butt end, an eraser holder detachably and reversibly fitted to the ferrule, and an eraser block held in the holder and longitudinally adjustable therein, 55 substantially as described.

3. A lead pencil provided with a ferrule at its butt end, an eraser holding open ended sleeve fitted to the ferrule for insertion and removal at both ends, and an eraser block 60 in the holder projecting at both ends therefrom and longitudinally adjustable therein, substantially as described.

4. A lead pencil provided with a ferrule at its butt end, an open ended eraser holding 65 sleeve, screw-threaded at each end and each end fitted for insertion in and removal from the ferrule, and an eraser block in the holder projecting at each end therefrom and longitudinally adjustable therein, substantially 70 as described.

5. An open ended eraser holding sleeve, screw threaded at each end and each end fitted for insertion in and removal from a ferrule or tube, an eraser block in the holder 75 projecting at each end therefrom and longitudinally adjustable therein, and a screw threaded ferrule or tube into which the holder fits, substantially as described.

In testimony, whereof I have signed my name to this specification in the presence of two subscribing witnesses.

BYRON B. GOLDSMITH.
